ROD MILL

Kálmán Z. Huszár, Cincinnati, Ohio

Original application December 29, 1941, Serial No. 424,839. Divided and this application November 13, 1944, Serial No. 563,240

2 Claims. (Cl. 241—171)

This invention relates to a rodmill for crushing, pulverizing or mixing materials, such as dye, face powder, or the like, and is a division of my co-pending application, Serial No. 424,839, filed December 29, 1941, for Rodmill now Patent Number 2,367,585, dated January 16, 1945.

An object of this invention is to provide in a pulverizing mill an improved means whereby the ground material may be selectively discharged therefrom during the rotation of the mill.

Another object of this invention is to provide in a pulverizing mill of this kind, an improved means whereby the ground material may be removed from an end of the mill and retained in a chamber at one end of the mill for rotation with the mill and subsequently discharged from the collecting chamber as the mill rotates.

To the foregoing objects, and others which may hereinafter more fully appear, the invention consists of the novel construction, combination and arrangement of parts, as will be more specifically referred to and illustrated in the accompanying drawing, but it is to be understood that changes, variations, and modifications may be resorted to which fall within the scope of the invention as claimed.

Figure 1 shows a side elevation partly in longitudinal section of a pulverizing mill constructed according to an embodiment of this invention.

Figure 2 is an end view of the mill showing the radially disposed housings, and the opposite side walls of the housings. All other details have been omitted, namely the crank handle, the carriage with its supporting tracks and the base with the rollers.

Referring to Figure 1, the numeral 10 designates generally a pulverizing mill member which is rotatably supported on a base structure 11. The mill member 10 includes a cylindrical body 12 containing a number of pulverizing units or bars 13. The cylindrical body 12 is formed with an opening 14 through which the material is charged for filling the mill. The closure member 15 is adapted to be removably secured to the cylindrical wall 12 for closing the filling opening 14.

A forward end wall 16 is secured to one end of the cylindrical body 12 and a rear end wall 17 is secured to the opposite end of the cylindrical wall 12. A trunnion 18 is secured to the end wall 16 and is rotatably supported in a bearing 19 carried by an upstanding bearing support 20 which is fixed to the base 11 and braced by means of one or more bracing members 21. The cylindrical body 12 adjacent the end wall 17 thereof has secured to the outer peripheral surface thereof

a circular track or rail 22, which engages a pair of spaced apart rollers 23 carried by bearing members 24 which are fixed to the base 11.

A ring gear 25 is fixed to the outer side of the end wall 16 and is adapted to mesh with a driving pinion 26 carried by a shaft 27. The shaft 27 is connected to a reduction gearing 28 of conventional construction which has connected therewith a driving wheel 29. The driving wheel 29 may be operated in any suitable manner from a power member (not shown).

The end wall 17 has secured thereto a pair of diametrically opposed and outwardly extending or offset housings 30 and 31. The housing 30 is formed of an outer side wall 32 and opposite end walls 33, thereby forming a pulverized material receiving chamber 34. The outer end of the housing 30 has an outer end wall 35 which is connected with the walls 33 and with the wall 32, and is outwardly offset from the outer marginal edge of the end wall 17. An inwardly extending wall 36 is connected at one end to the forward end of the outer wall 35, and at the other end is fixed to the peripheral surface of the cylindrical body 12 forwardly of the end wall 17.

The cylindrical wall or body 12 is formed with an opening 37 communicating with the passage 38 formed by the wall 36, so that when the housing 30 is in a lowermost position, the pulverized material will flow downwardly through the opening 37 and the passage 38 into the lower portion of the housing 30. The inner portion of the housing 30 is connected to the inner portion of the housing 31 by means of an annular connecting wall 39 which, as shown in Figure 1, is inwardly offset from the outer walls of the two housings 30 and 31.

The housing 31 is similar in every detail to the construction of the housing 30, the cylindrical wall 12 being formed with a discharge opening 40 adjacent the end wall 17 which communicates with the chamber 41 through a passage 42 similar to the passage 38.

End wall 17 is provided with an annular enlargement or boss 63 within which a bearing sleeve 64 engages and the bearing 64 at its outer or rear end is formed with an annular flange 65 engaging against the outer side of the enlargement or boss 63. A manually operable valve generally designated as 66 is loosely mounted at its inner end in the bearing sleeve 64.

An outer bearing sleeve 67 is carried by the housings 30 and 31, and the outer end portion of the valve member 66 also rotatably engages

in the bearing sleeve 67. The valve member 66 is formed of a cylindrical body 68 having an inner end wall 69 fixed thereto. An outer end wall 70 is also fixed to the outer end of the cylindrical body 68, and an inclined plate 71 is fixed at its outer end to the outer end wall 70, and its inner end to an inner wall 72 which is disposed outwardly from the inner end wall 69. The cylindrical body 68 is formed with an opening 73 communicating with the discharge passage 74 formed by the inclined plate 71. The outer end wall 70 is formed with an opening 75 therethrough, so that the material discharged into the valve member 66 through the opening 73 will flow downwardly over the wall 71 and out through the discharge opening 75 formed in the end wall 70.

The valve member 66 is fixedly secured as by welding 76 or the like to a valve operating shaft 77. The shaft 77 extends through an opening 78 formed in the plate 71, and is also journalled in a bearing 79 which is carried by a horizontally shiftable carriage 80. A material delivery spout or nozzle generally designated as 81 is fixedly secured to the carriage 80 and is formed at its upper end with a cylindrical sleeve 82 loosely engaging about the bearing sleeve 67. A sealing gasket 83 may be interposed between the sleeve 82 and the bearing member or sleeve 67. The spout or nozzle 81 is formed with a bearing boss 84 through which the shaft 77 rotatably engages. The shaft 77 also is journalled at its outer or rear end portion through a bearing member 85 which is carried by a frame structure 86 forming part of the carriage 80.

The carriage 80 includes upstanding pairs of arms 87 having rollers 88 journalled thereon, which are adapted to movably engage over carriage supporting tracks 89 supported above the shaft 77 and extending rearwardly from the mill 10. A crank or handle 90 is fixed to the rear end of the shaft 77 and when the crank 90 is in a lowermost position, which is the position shown in full lines, the valve member 66 will be disposed as shown in full lines in the drawing to discharge the material from the mill 10. When the handle 90 is raised to the dotted line position, the valve member 66 will be rotated through an arc of 180 degrees thereby positioning the discharge opening 73 lowermost, so that the material dropping from the uppermost of the housings 30 or 31 will be held from discharge into the delivery nozzle 81.

In the use and operation of this mill during the initial grinding or pulverizing of the material, valve member 66 is turned to position the opening 73 lowermost. The material which is pulverized or ground in the mill 10 will move outwardly through passages 37 or 40, as these passages are alternately lowermost, and will enter the collecting housing 30 and 31. The material may be collected in the collector for the desired period of time and then handle 90 may be swung downwardly to the full line position, thereby placing the discharge opening 73 uppermost. The

material will then drop through opening 73, moving along inclined wall 71 and then outwardly into spout 81.

What I claim is:

1. In combination a pulverizing mill including a rotatable body formed with a cylindrical side wall and opposite end walls, a number of radially disposed housings carried by one of said end walls, each housing comprising a rear wall and opposite side walls fixed to said one end wall, said cylindrical wall having opposed openings, passage forming means fixed to said housings and extending outwardly therefrom, said passage forming means communicating with said housings and encompassing said openings, means forming an annular valve seat between the adjacent ends of said rear walls, said one end wall having an axial opening, a cylindrical valve engaging in said valve seat and said axial opening, said valve including a cylindrical body formed with a peripheral opening between said one end wall and said valve seat, an inclined guide disposed interiorly of said cylindrical valve and inclined outwardly from the inner end of said opening whereby the material in an uppermost housing will be guided outwardly through the valve when said valve opening is in an uppermost position, a discharge nozzle encompassing said valve seat, means supporting said nozzle, and means extending through said nozzle connected with said valve for adjusting the position thereof.

2. In combination a pulverizing mill including a rotatable body formed with a cylindrical side wall and opposite end walls, a number of radially disposed housings carried by one of said end walls, each housing comprising a rear wall and opposite side walls fixed to said one end wall, said cylindrical wall having opposed openings, passage forming means fixed to said housings and extending outwardly therefrom, said passage forming means communicating with said housings and encompassing said openings, means forming an annular valve seat between the adjacent ends of said rear walls, said one end wall having an axial opening, a cylindrical valve engaging in said valve seat and said axial opening, said valve including a cylindrical body formed with a peripheral opening between said one end wall and said valve seat, an inclined guide disposed interiorly of said cylindrical valve and inclined outwardly from the inner end of said opening whereby the material in an uppermost housing will be guided outwardly through the valve when said valve opening is in an uppermost position, a discharge nozzle encompassing said valve seat, means supporting said nozzle, means extending through said nozzle connected with said valve for adjusting the position thereof, said latter means including a valve shaft disposed axially of said valve seat, means supporting said valve shaft for rotary movement, and operating means for said valve shaft.

KÁLMÁN Z. HUSZÁR.
